UNITED STATES PATENT OFFICE.

JOHN HENRY BLAKE, OF WASHINGTON, DISTRICT OF COLUMBIA.

MAGAZINE-FIREARM.

1,194,270.

Specification of Letters Patent.

Patented Aug. 8, 1916.

Application filed April 7, 1915. Serial No. 19,838.

To all whom it may concern:

Be it known that I, JOHN HENRY BLAKE, a citizen of the United States, residing at Washington, District of Columbia, have 5 invented certain new and useful Improvements in Magazine-Firearms; and I do hereby declare the following to be a full, clear, and exact description of the invention, such as will enable others skilled in the 10 art to which it appertains to make and use the same.

My present invention relates to that class of magazine repeating firearms or shoulder rifles that is capable of having the 15 magazine charged by filled cartridge clips of five or seven or more cartridges.

The invention consists also in improved breech mechanism, improved firing mechanism, improved feed mechanism, improved 20 cartridge case extractor mechanism, and in various other details of construction, and combinations and constructions of parts hereinafter more fully described and claimed.

25 My invention also relates to an improvement in magazine firearms, and has for its object to provide a rifle capable of use either for single or magazine firing and a simple and quickly operated cut off by means of 30 which the magazine may be brought into or thrown out of action as desired, the magazine charge when not in action remaining in the gun.

35 My invention is especially intended to provide improvements over the magazine in my former Patent No. 608023, granted July 26, 1898, and entitled Magazine bolt-gun.

40 My invention will be more fully understood by reference to the accompanying drawings, in which the same parts are indicated by the same reference symbols throughout the several views.

45 Figure 1 shows a central vertical section through the breech of the barrel and the receiver, and shows the cartridge clip and the breech bolt in elevation, the breech being in the open position; Fig. 2 shows a section along the line 2—2 of Fig. 1, and looking down; Fig. 3 is a similar section to 50 Fig. 1, but as seen from the reverse direction, and illustrates the mechanism for rotating the cartridge clip, the same being in the inoperative position; Fig. 4 is a similar view to Fig. 3, but shows the feed mechanism in the operative position; Fig. 5 is a similar view to Fig. 1, but shows the breech

closed, and the firing pin in the cocked position; Fig. 5^a is a detail showing the operation of the safety lock carried by the firing pin; Fig. 6 shows a longitudinal vertical section, on a larger scale, of the breech bolt as removed from the gun, with parts carried thereby, parts being shown in elevation; Fig. 7 shows a section along the line 7—7 of Fig. 6, and looking in the direction of the arrows; Fig. 8 shows a section along the line 8—8 of Fig. 6, and looking in the direction of the arrows; Fig. 9 shows a section along the line 9—9 of Fig. 6 and looking in the direction of the 60 arrows; Fig. 10 is an end view of the breech bolt as shown from the right of Fig. 6; Fig. 11 shows a section through the receiver of the gun along the line 11—11 of Fig. 3, and looking toward the muzzle of 65 the piece, and shows the clip in the inoperative position; Fig. 12 is a similar view to Fig. 11, but shows a section along the line 12—12 of Fig. 4, and shows the clip in the operative position; Fig. 13 shows a section 70 through the receiver along the line 13—13 of Fig. 1, and looking toward the breech; Fig. 14 shows a section along the line 14—14 of Fig. 1, and looking toward the breech; Fig. 15 is a detail showing the extractor in 75 perspective; Fig. 16 is a detail showing the breech bolt stop and ejector in perspective; Fig. 17 is a detail showing in perspective the bell-crank lever for operating the feed 80 clip; and Fig. 18 is a perspective view of 85 the cut off lever for throwing the magazine feed mechanism into and out of engagement.

The principal parts of the piece, briefly 90 enumerated, are as follows:

A represents the barrel of the gun; B, the receiver; and C, the magazine housing connected at the front end to the fore stock D and at the rear end to the rear stock E.

F represents the magazine door hinged 100 to and closing the lower part of the magazine chamber; G, the rotary clip carrying the cartridges; H, the breech bolt; I, the extractor; and I', the shell starter coacting with the extractor.

K represents the bolt stop and ejector; L, the feed door; M, the sear; N, the sear spring; and P, the trigger.

Q represents the firing pin; Q', the cocking piece; Q², the removable striker on the 110 firing pin; and Q³, the safety lock carried by the firing pin.

R represents the pawl for holding the magazine against rotation when the feed dog is not in operation, and S, the cut off lever for shifting from hand firing to magazine fire.

A represents the barrel which is secured to the receiver in the usual way and is provided with two slots 1 and 2 for the claw of the extractor and of the cartridge starter, respectively. The receiver B is secured at one end to the barrel and at the other end to the stock E, and is mounted above the magazine housing C which is closed by the door F, hinged to the housing C, as at 3, and locked at the other side by a spring catch 4, as shown most clearly in Figs. 11 and 12.

The receiver has on its left-hand side a broad and deep groove 5 for the passage of the left locking lugs of the bolt, and on the opposite side a similar groove 6 for the passage of the opposite locking lugs of the breech bolt; while in its forward portion the receiver is provided with a locking chamber B', into which chamber B' project the segmental ribs 7, there being formed on each side of said segmental ribs 7 annular grooves 8 and 9, with shoulders 10 and 11 in rear of said grooves, against which shoulders the locking lugs of the breech bolt engage when the bolt is turned to the locking position.

The bottom of the receiver is provided with a groove 12, inclined upward slightly, as shown in Figs. 1, 3, 11 and 12, to guide the nose of the cartridge into the loading position. Near the forward end the receiver is provided with a slot 13 in which the cartridge starter I' is pivoted, as shown in Fig. 2, and near its rear it is provided with two slots 14 and 15, see Fig. 2, to receive the inwardly-projecting lugs of the ejector and bolt stop K, which is hinged to the receiver, as at 16. The receiver is also provided with suitable slots 17 in its bottom for the feed dog L and for the sear M. The receiver is also notched, as at 18, see Figs. 2 and 5^a, to permit the handle of the bolt to swing down into said notch.

The rotary clip G is provided with trunnions 20 engaging in notches in the receiver, and the cartridges are attached in the usual well known way. Near the rear end of this clip, I provide a polygonal plate 21 having ratchet teeth 22 to engage the feed dog L, and with holes or sockets 23 to engage the pawl R for holding the magazine against rotation backward, or at any time except when fed forward by the feed mechanism.

The breech bolt H is made in the form of a hollow sleeve to receive the firing pin, and is provided with a handle H' terminating in the knob 25. This handle is preferably bent, as at 26, so as to lie close alongside of the piece, and out of the way, when the bolt is in the closed and locked position, as shown most clearly in Fig. 5^a. The head of the bolt

is cup-shaped, as shown in Figs. 6 and 10, to receive the base of the cartridge case, and is provided with two pairs of lugs 27, 27^a and 28, 28^a, having shoulders 29 and 30 adapted to engage the corresponding shoulders 10 and 11 of the receiver. The lugs 27 and 28 are cut away, as at 31 and 32, to permit the forward end of the extractor to swing over the same, as the breech bolt is rotated incident to the locking or unlocking of same. In rear of the lug 27 I provide an arcuate groove 33 to engage the lip 34 of the extractor I.

The hollow breech bolt H is provided with a slot 35, which is elongated, as at 36, to permit the free entry of the lug 37 on the interior of the extractor, which has an overhanging rib 38 adapted to hook over the front wall 39 of the slot 35 and to hold the extractor on the breech bolt when the parts are assembled. The inner face of this extractor is arcuate to fit snugly over the breech bolt and to permit the same to be held against rotation while the breech bolt is rotated.

The extractor consists of two parts—the body portion 40 and the spring head 41 which terminates in the claw 42, and which spring head is connected to the body portion by an elliptical lug 43 adapted to be projected into a lateral slot 44 in the body portion 40, and to be turned to the locking position, as shown in Fig. 15. The spring head of the extractor is sprung into a notch between the rib 45 and the lug 46, see Figs. 1 and 15; thus the head of the extractor may be readily applied to or removed from the body thereof, and the extractor itself may be readily connected to or removed from the breech bolt when desired.

To supplement the work of the extractor I provide the shell starter I', shown in Figs. 1, 2, 11 and 12, which is in the form of a bell-crank lever pivoted to the receiver, as at 50, and having two claws. The front claw 51 is adapted to engage the rim of the cartridge case, and the rear claw 52 is adapted to engage in rear of the front lug on the breech bolt when the latter is drawn to the rear, so that the rearward movement of the breech bolt will swing the bell-crank lever about its pivot, causing the claw 51 to bite against the side of the cartridge case and to engage against the front face of the rim thereof at the same time that the extractor bears against the opposite side of the cartridge case, and engages the rim thereof on the opposite side.

The result of the joint action of the cartridge starter and of the extractor is that the cartridge case is centered in the chamber and is pressed rearward from both sides at the same time, until it is drawn rearward far enough to become thoroughly loosened in the chamber of the barrel, which chamber, as usual, is slightly tapered to the rear. This

cartridge starter acts only through a small movement of the cartridge case rearward, but its action is sufficient to supplement that of the extractor, and to insure that the cartridge case is readily withdrawn, obviating the tendency, which exists where a single extractor, operating at one side of the cartridge case only is used, to bind the cartridge case in the chamber.

10 Since the empty cartridge cases often tend to stick in the chamber, this combined action of the extractor and of the cartridge starter secures positive and effective means for starting the empty cartridge case with the 15 application of a comparatively small amount of power; the result being that the force required to draw the breech bolt to the rear, incident to starting the cartridge case from its seat, is in a large measure decreased, and 20 the mechanism is caused to operate much more smoothly.

The breech bolt is provided near its rear with a locking lug 53, which is slotted longitudinally to permit the passage of the upper 25 arm of the sear, and with a second lug 54, which lugs engage and control the arm 94 of the feed dog L; thus the lug 54 locks the dog by pushing the arm 94 forward as the breech is being closed, and the divided lug 30 53 holds it locked and in the depressed position when the breech bolt is in the closed and locked position.

The firing pin Q is mounted in the hollow breech bolt and is provided at its rear end 35 with a cocking piece Q', and at its front end with a removable striker Q², shown in detail in Figs. 6 and 9. This striker is provided with a recess 60, opening at one side, as at 61, and having an annular groove 62 into 40 which the flanged head 63 of the body portion of the firing pin Q engages, as shown most clearly in Fig. 6. This head is locked in place by a sliding collar 64, pressed over the reduced rear end 65 of the striker by the 45 coil spring Q⁴ which normally presses the firing pin forward into the firing position.

The cocking piece Q', which is screwed on to the body portion of the firing pin, is provided with the usual lug 70 to engage the 50 arm 71 of the sear M, and also with the cocking lug 72 which has the cam face 73 engaging with the cam face 74 on the breech bolt, and holding the firing pin in the cocked position while the breech bolt is being reciprocated in the receiver. Now when the handle H' of the breech bolt is turned down to the position shown in Fig. 5^a, the two cams 73 and 74 will be disengaged, and the firing pin would fly forward under the action of its spring were it not retained in the cocked 55 position by the lug 70 engaging the arm 71 of the sear M, as shown in Fig. 5.

The cocking piece is provided with the usual head 75 for convenience of assembly, 60 and this head is provided with a forwardly-

projecting pin 76, see Figs. 1, 3, 6 and 7, which projects into a segmental slot 77 in the safety lock Q³, and limits the movement of this lug from the horizontal position shown in Figs. 1, 2, 3, 6, 7 and 8 to the vertical position shown in Fig. 5^a. This safety lock carries a spring catch 78, adapted to spring into engagement with the corresponding catches in the head 75, and thus to hold the safety lock Q³ in either the vertical or the horizontal position, and yet permit the same to be readily shifted by hand when desired. When this safety lock is in the vertical position as shown in Fig. 5^a, its short arm 79 engages in front of a shoulder 80 80 on the receiver, which is shown in dotted lines in Fig. 2 and in full lines in Fig. 5^a. Thus when the breech bolt is in the closed and locked position, if this safety lock is turned to the vertical position shown in Fig. 5^a it will hold the firing pin rearward, whether the trigger be pulled or not; and the piece cannot be fired while this safety lock is in the vertical position, shown in Fig. 5^a.

I provide in a single piece K a combined bolt stop and ejector, shown in operation in Fig. 2, and in detail in Fig. 16, which part K is hinged to the receiver, as at 16, and is provided with the bolt stop lug 90 which projects into the path of the lug 27^a of the breech bolt, and prevents the breech bolt from being drawn out of the receiver unless the lug 90 be drawn out of engagement. The forward end of the lever K is provided with 10 an ejector lug 91, which projects into the path of the base of the cartridge case, and by suddenly arresting the rearward movement of the cartridge case will whip it out to the right of the gun through the opening in the 15 side of the receiver.

The ejector lug 91 is normally pressed inward by means of the ejector spring 92 mounted on the back of the ejector, shown in section in Fig. 14, and in dotted lines in Fig. 2. The inner end of the ejector lug is normally pressed against the breech bolt by this spring; and when the breech bolt is drawn to the nearly open position, this ejector lug passes into the recess 93 in the forward end of the breech bolt (see Fig. 10), and brings up against the rear face of the cartridge case which is being drawn rearward by its engagement with the extractor L.

The sear M is pivoted on the pin m and has three arms including the cocking arm 71 to engage the cocking lug on the cocking piece, the arm m' to engage the trigger P, and the arm m² to engage the sear spring N. This sear spring is wound on the pin n and has one end engaging the arm m² of the sear, and its other end engaging the back of the pawl R, as shown most clearly in Fig. 14.

The turning of the rotary clip for feeding the cartridges *seriatim* is accomplished by the feed dog L shown most clearly in Figs. 3, 4 and 17. This dog L is pivoted on the same pin m as the sear, and has an upright arm 94 which normally lies in the path of the lugs 27^a of the breech bolt and is struck thereby, causing the feed arm 95 to engage one of the ratchet teeth 22 of the clip and to feed the clip forward one tooth every time the breech bolt is drawn to the rear. The forward movement of the breech bolt causes the lug 54, near the rear end of the breech bolt, to force the arm 94 forward again, thus withdrawing the feed arm 95 and placing the dog in position to feed another cartridge.

In order to cut out the magazine firing and fire wholly by hand when desired, I provide a cut-off lever S, shown in Figs. 14 and 18, which has its hub s cut away as shown in Fig. 18, and provided with shoulders s' to engage corresponding shoulders 96 on the hub 97 of the dog L. When this cut-off lever S is moved to its upper position, as shown in Fig. 5, it throws the arm 94 of the dog to the position shown in Fig. 3 so that it is entirely clear of the lugs on the breech bolt, while when the cut-off lever is thrown to the lower position there is sufficient play between its hub and the hub of the dog to permit the arm 94 to swing up into the engaging position shown in Fig. 4.

The operation of the device is as follows:

35. To charge the piece open the magazine door F, insert the clip which, owing to the shape of the magazine chamber, will be centered so that the trunnions of the clip will engage in the bearings in the magazine chamber, then
40. close the door, withdraw the breech bolt to the rear, and forcing it forward again will cause the feed of a cartridge to the chamber of the barrel, and by turning the bolt to the right the piece is cocked and ready for
45. firing; the act of firing being completed by pulling the trigger. If it is desired to load by hand without using the charge in the clip, throw the cut-out lever S to the proper position, thus throwing the feed dog L out
50. of operation, and the piece may be loaded by hand and fired single shot indefinitely, while maintaining the full charge in the magazine. Thus it will be seen that when unloaded by hand there will be seven cartridges in the
55. magazine and one in the barrel, making eight in all in the piece at the same time, and firing by hand can be continued indefinitely with the magazine full charged, while the magazine can be thrown into operation
60. by simply shifting the cut-out lever to the proper position. If it is desired to hold the piece in the safety position when ready, after the breech bolt has been moved to the forward position, closing and locking the
65. barrel, and incidentally feeding a cartridge

into the chamber, turn up the safety lock to the vertical position, as shown in Fig. 5^a, and the piece cannot be fired, whether the trigger be pulled or not. When this safety lock is turned down to the horizontal position, the piece can be readily fired as before.

It will be noted that the magazine chamber is of wide flaring bottom, and when the door is open and the clip inserted from beneath the cylindrical clip is automatically centered in the magazine chamber, so that the trunnions will engage in the corresponding notches in the same, and the clip can be inserted without actual inspection by the soldier from the sense of feeling alone. Moreover, I provide a positive feed for the individual cartridges, which is automatically operated by the reciprocating movement of the breech bolt, and which does not depend upon the function of any spring. Such springs are likely to become injured, or to become clogged up, or to fail from other reasons, and also take up room; while the herein described feeding mechanism is contained in the body of the gun, does not take up unnecessary space, and is effectually screened from injury from any ordinary accident. Moreover, the positive feed enables the full strength of the operator to be used in feeding the cartridge in front of the bolt, so that the cartridge may be ready on its forward movement to be pushed into the chamber of the barrel.

By the herein described feed mechanism the cartridges may vary in length, and varying shapes of nose may be used, thus the shape and weight of the bullet may be varied without in any way affecting the efficiency of the piece. Thus, if the bullets were of round or pointed ends, and each cartridge entirely separated from the adjacent cartridges, there would be no danger of the point of one bullet striking the primer of the cartridge in front of the same with sufficient force as to cause an explosion in the magazine, which accident is likely to happen where pointed cartridges are used in the ordinary magazines using center fire cartridges. Furthermore the herein described construction presents a very simple arrangement which combines the advantages of the single shot rifle, with repeaters, in a single piece. Again, by having the safety lock near the end of the breech bolt, and substantially in the line of sight, the soldier can unavoidably note when sighting the gun whether the safety lock is in the raised position or not, whereas when this safety lock is located on the side of the gun, or in any less prominent position, the soldier in excitement of action may fail to note whether his piece is in a safety position or not. It is a matter of record that in target practice, as well as in action, many instances are found in which the soldier has been using

his piece, or thought he was using it, with the firing pin in a safety position and not a single cartridge in the gun exploded.

Another advantage of the piece herein described is that an empty shell when extracted and ejected is thrown to the right of the piece and away from the operator, instead of upward and to the rear, as in many weapons; the result being that the operator's 10 eyes, or glasses if he uses them, are not liable to injury from ejected cartridge cases. Again, the rotary clip is large enough to give a good finger hold, and in cold weather with gloves or mittens on may be readily inserted in the magazine. Furthermore the 15 magazine may be quickly opened to examine, or refill, or remove the packet, or to replace any cartridges that have been fired. The magazine, therefore, needs no indicator. 20 Again in case of jammed cartridges due to double loading, the jam may be instantly removed by opening the magazine doors and allowing the clip to drop out, or removing same. A number of loaded clips may be 25 carried, but the same clip may be kept in the magazine and refilled many times by hand with single cartridges.

By having the nose of the breech bolt cup-shaped as shown, in case of a ruptured shell, 30 or of the primer being pierced by the firing pin, the powder gases are prevented from blowing back in the face of the operator. By having the cartridges contained in a single revolving clip, with which the magazine 35 is charged in one movement, uniform balance of the rifle whether the magazine is full or empty is secured. This is assured by the magazine being centrally located immediately in front of the trigger guard, so that 40 the position of the center of gravity is not substantially altered as each shot is fired, or whether the magazine be full or empty. The piece cannot be fired unless fully locked, or if the trigger is pulled before the locking 45 lugs are properly seated the action of the nose of the cocking piece on the side of the cam of the bolt will throw the bolt to the right, seating the lugs before the point of the firing pin reaches the primer.

50 It will be seen that the cartridge starter acts like the claw of a claw hammer and starts the cartridges simultaneously, pressing the cartridge over against the oppositely-disposed extractor, and the two conjointly center the empty cartridge case and push or pull it to the rear until it has well started from the chamber, thus obviating the danger 55 of the empty cartridge case binding in the chamber of the extractor, pulling away 60 part of the rim of the empty cartridge case and leaving the same in position in the chamber which would render the gun entirely useless until the empty cartridge case was removed, either by a ram rod, or in any 65 other convenient way. It will be seen that

there is a single piece—to wit:—the breech bolt which transmits to the receiver all the strain of firing, and that the breech bolt has double sets of bearing shoulders at its front, and bearing shoulders at its rear to take up 70 said strain; thus providing a very simple, strong and effective arrangement for the purpose stated. By having the handle of the breech bolt bent, as shown, it is caused to lie close to the side of the gun when the 75 piece is in the loaded position, or in the position in which it is ordinarily carried, thus being out of the way.

The breech bolt is held in place against being accidentally withdrawn rearward by 80 a lug on the breech bolt stop and ejector, and this lug may be conveniently sprung out of the way, and the breech bolt withdrawn entirely from the piece, leaving the bore of the barrel open at both ends with 85 a free line of sight therethrough, so that it may be readily inspected and cleaned. Furthermore the extractor may be readily applied to or removed from the breech bolt when the latter is removed, and the firing 90 pin may also be readily detached for purposes of inspection, cleaning, or repair. Also, the other parts of the mechanism are 95 of very simple and durable construction and are not liable to get out of order, and are readily accessible for purposes of inspection, cleaning, or repair.

It will be noted that the gun may be readily and rapidly fired either from the shoulder or from the hip as may be desired, 100 and that there is no danger of cutting or jamming the fingers with lever actions, all of the parts to be operated by hand being in such shape and so located as not to cause accidents of the character referred to. 105 Finally it will be seen that the entire mechanism is of extremely simple and durable construction, and that any gun-smith or mechanic can readily put same in repair, or make extra parts if required, and that there is little likelihood of any of the parts getting out of order if given only a small proportion of the ordinary care required for similar weapons.

115 I claim as my invention:—

1. In a firearm the combination with a barrel provided with a chamber, and a recess at each side of said chamber, of a reciprocating breech bolt adapted to close the barrel, said reciprocating breech bolt being provided with an undercut flange adapted to engage the end of the body of the extractor, an extractor carried by said breech bolt and having a lip engaging said undercut flange on the breech bolt, and having its head adapted to project into one of said recesses in said barrel, a shell starter mounted in the opposite recess of said barrel and actuated by the rearward movement of said breech bolt, and adapted to coöperate with 120 125 130

said extractor in centering the cartridge case in the chamber and starting same to the rear, and a combined bolt stop and ejector located in the path of said breech bolt and provided with a lug adapted to engage the rim of the cartridge case opposite to said extractor and to eject the same, and with a second lug adapted to arrest the rearward movement of said breech bolt, substantially as described.

2. In a firearm the combination with a barrel provided with a chamber, and a recess at each side of said chamber, of a reciprocating breech bolt adapted to close the barrel, said reciprocating breech bolt being provided with an undercut flange adapted to engage the end of the body of the extractor, an extractor carried by said breech bolt and having a lip engaging said undercut flange on the breech bolt, and having its head adapted to project into one of said recesses in said barrel, a shell starter in the form of a bell-crank lever having one arm adapted to be struck by the rearward movement of said breech bolt, and the other arm terminating in a claw adapted to engage the rim and sides of the cartridge case and to co-act with the extractor in centering said cartridge case and starting same to the rear, and a combined bolt stop and ejector located in the path of said breech bolt and provided with a lug adapted to engage the rim of the cartridge case opposite to said extractor and to eject the same, and with a second lug adapted to arrest the rearward movement of said breech bolt, substantially as described.

3. In a firearm the combination with a hollow breech bolt, of a firing pin mounted therein provided with a cylindrical stem and a flanged annular head, a striker removably mounted on said head and provided with a recessed groove opening laterally and adapted to receive said flanged head of the firing pin, said striker terminating at its rear in a reduced cylindrical portion, a locking ring surrounding said firing pin and adapted to slip over said reduced cylindrical portion of the striker, and a coil spring adapted not only to impel the firing pin forward when said firing pin is released, but also to press against the base of said locking ring and to hold said locking ring in the engaging position for locking said striker in place on the firing pin, substantially as described.

4. A firing pin provided with a cylindrical stem and a flanged head, a striker removably mounted on said head and provided with a recessed groove opening laterally and adapted to receive said flanged head of the firing pin, said striker terminating at its rear in a reduced cylindrical portion, and a locking ring surrounding said cylindrical stem and adapted to slip over said reduced cylindrical portion of the striker, substantially as described.

5. A firing pin provided with a cylindrical stem and a flanged head, a striker removably mounted on said head and provided with a recessed groove opening laterally and adapted to receive said flanged head of the firing pin, said striker terminating at its rear in a reduced cylindrical portion, and a locking ring surrounding said cylindrical stem and adapted to slip over said reduced cylindrical portion of the striker, with means for holding said locking ring in place when said firing pin is in use, substantially as described.

6. A firing pin provided with a cylindrical stem and a flanged head, a striker removably mounted on said head and provided with a recessed groove opening laterally and adapted to receive said flanged head of the firing pin, said striker terminating at its rear in a reduced cylindrical portion, and a locking ring surrounding said cylindrical stem and adapted to slip over said reduced cylindrical portion of the striker, in combination with a coil spring surrounding the stem of said firing pin and adapted to impel the firing pin forward when released from the cocked position, and also to hold said locking ring in place for locking said striker to the stem of the firing pin, substantially as described.

7. In a firearm the combination with a receiver and a reciprocating breech bolt mounted therein, and provided near its heel with lugs, and adapted to rotate laterally for locking and unlocking same, of a magazine chamber mounted below said receiver, a rotary clip mounted in said magazine, and a feed dog pivoted in said receiver and operated by said breech bolt, and held in the locked position by said lugs on the heel of said breech bolt, substantially as described.

8. In a firearm the combination with a receiver and a reciprocating breech bolt mounted therein, and provided with locking lugs on the head thereof, and with additional lugs near its heel, and adapted to rotate laterally for locking and unlocking same, of a magazine chamber mounted below said receiver, a rotary clip mounted in said magazine, and a feed dog pivoted in said receiver and operated by one of the lugs on the head of said breech bolt, and held in the locked position by said lugs on the heel of said breech bolt, substantially as described.

9. In a firearm the combination with a hollow reciprocating breech bolt, of a firing pin, a spring mounted in said hollow breech bolt, a cocking piece carried by the rear end of said firing pin, and provided with an enlarged head at the rear end thereof, with a pair of notches set at an angular distance apart on the front side of said head, said cocking piece being also provided with a cylindrical stem in front of said head, and

a safety lock revolvably mounted on said cylindrical stem and adapted when turned in one position to permit the free movement of said firing pin, but when turned in another position to engage an abutment on said breech bolt, with a spring plunger carried by said cocking piece and adapted to

engage in one or the other of said notches for holding the safety lock in either the engaging or the disengaging position, substantially as described.

In testimony whereof, I affix my signature.

JOHN HENRY BLAKE.
